UNITED STATES PATENT OFFICE.

WILLOUGHBY S. SCOVILLE, OF WEST DE PERE, WISCONSIN.

DRIVING MECHANISM FOR VALVE-GRINDERS.

1,324,280.

Specification of Letters Patent.

Patented Dec. 9, 1919.

Application filed June 15, 1917. Serial No. 174,922.

To all whom it may concern:
Be it known that I, WILLOUGHBY S. SCOVILLE, a citizen of the United States, residing at West De Pere, in the county of Brown and State of Wisconsin, have invented certain new and useful Improvements in Driving Mechanism for Valve-Grinders; and I do hereby declare the following to be a full, clear, and exact description of the invention, 10 such as will enable others skilled in the art to which it appertains to make and use the same.

This invention relates to a valve grinding machine and has for one of its objects to 15 provide the device with means for frictionally driving the valve turning mechanisms in contradistinction to the machines now upon the market which either employ mutilated gears and pinions or pins and arms 20 for operating the valve turning mechanisms.

Another object of this invention is to provide means for turning the valve or valve seat grinding tool in an alternate to and fro direction but turning the valve or valve seat 25 grinding tool a greater distance in one direction than in the other.

Another object of this invention is to provide a flexible connection between the driving mechanisms and the valve or valve seat 30 grinding tool whereby the valve or tool may be readily moved in any lateral direction with respect to the driving mechanisms.

Another object of this invention is to provide the flexible connection between the 35 driving mechanisms and the valve or tool with a telescopic connection whereby the bit for the valve or tool may be moved inwardly or outwardly in a longitudinal direction with respect to the flexible connection.

Another object of this invention is to provide a valve grinding machine which consists of few parts, efficient and durable, and which can be sold upon the market at a nominal cost.

These and other objects and advantages will more fully appear as the nature of the invention is more clearly understood from the following description taken in connection with the accompanying drawings wherein I have disclosed a preferred embodiment of the invention, but which is susceptible to various alterations and modifications in the conformation, construction 50 and arrangement of parts thereof without departing from the spirit of the invention 55

or exceeding the scope of the appended claim.

In the drawings,

Figure 1 is an end view of the device, the 60 flexible connection being shown as partly broken away.

Fig. 2 is a side view of the device shown in Fig. 1.

Fig. 3 is a side view, partly broken away 65 and partly in section, of a hand-hold and showing the telescopic connection therein between the shaft and the valve or tool bit carried by the hand-hold.

Referring to the drawings, wherein similar reference characters denote corresponding parts throughout the several views, 1 denotes the standards of the frame mounted upon the base 2 which is adapted to be secured to a ceiling or other suitable support 70 through the medium of the screw bolts 3 or other suitable securing means.

Suitably mounted in the opposing pairs of the standards 1 are the oppositely disposed registering journals or bearings 4 and 80 5, and revolubly mounted within the journals 4 and 5 is the driven shaft 6 having secured upon its projecting end at one side of the frame the driven pulley 7 which is adapted to be driven by a belt connection 85 with any suitable source of power, however, in smaller machines a crank handle (not shown) may be secured upon the end of the shaft 6 in lieu of the pulley 7 and the device may be hand-operated. 90

Secured upon the shaft 6 between the journals 4 and 5 is the broad-faced wheel 8 provided upon one of its peripheral edges with the outwardly inclined flange 9 which extends substantially half way around the 95 circumference of the wheel 8. The wheel 8 is also provided upon its other peripheral edge with the outwardly inclined flange 10 which is positioned upon the wheel 8 obliquely opposite to the flange 9 and extends 100 substantially one-third of the distance around the circumference of the wheel 8. The respective ends of the flanges 9 and 10, however, terminate with respect to each other in a manner to provide substantially 105 oppositely disposed gaps or spaces therebetween.

The standards 1 of each end pair are parallel to each other but the respective pairs converge toward each other and are 110 provided with the head 11. Suitably mounted through the head 11 is the bearing

12, which may be of any suitable form of bearing, but preferably a ball or roller bearing, and suitably journaled in the bearing 12 is the shaft 13 having upon its end 5 which projects within the frame the smooth-faced pinion 14 having its face transversely beveled so that the pinion 14 is substantially frusto-conical in formation. The pinion 14 is preferably positioned in vertical alignment with the wheel 8 and therebeneath and spaced from the wheel 8. The adjacent face of the pinion 14 is of a diameter equal to the width of the face of the wheel 8 and has its beveled face inclined to an angular 10 degree equal to the inclinations of the flanges 9 and 10 upon the wheel 8 so that the beveled face of the pinion 14 will be frictionally and efficiently engaged by the flanges 9 and 10 of the wheel 8 when either 15 of the flanges 9 and 10 is brought into engagement therewith for revolving the pinion 14 and the shaft 13 in a direction in accordance with whichever flange is in engagement with the pinion 14.

20 The shaft 13 has interposed therein at any suitable and desirable point the flexible member or connection 15, which is preferably in the nature of a coil as shown, and provides for any degree of lateral movement in 25 any direction of the free end of the shaft 13 with respect to that portion of the shaft 13 journaled in the bearing 12 of the frame. The outer end of the shaft 13 is provided with the head 16 for rotatably and slidably 30 mounting this end of the shaft 13 within the bore 17 of the hand-hold 18, this end of the shaft 13 being provided with the elongated longitudinally extending socket 19, preferably square in cross section, for slidably 35 mounting this end of the shaft 13 within the bore 17 of the hand-hold 18, this end of the shaft 13 being provided with the elongated longitudinally extending socket 19, preferably square in cross section, for slidably 40 or telescopically receiving the correspondingly shaped stem 20 secured upon the enlarged collar 21 of the bit 22, the collar 21 of the bit 22 being rotatably retained within the opposite end of the hand-hold 18 by the 45 sleeve 23 suitably threaded in this end of the hand-hold 18. The outer end of the bit 22 is provided with the head 24 provided upon its operating face with the diametrically disposed rib or lug 25 adapted to engage a 50 valve or any suitable form of valve seat grinding tool.

The operation of the machine and the advantages attained thereby will be briefly described as follows. The frame of the device is preferably secured to the ceiling with 55 in a shop or building and the engine or other suitable device having valves and valve seats to be ground is positioned substantially therebeneath and the power employed supplied to the driven pulley 7, which in turn will revolve the shaft 6, the wheel 8 and its flanges 9 and 10 in one direction. The valve or valve seat, or both as the case may be, and which have been operatively engaged by the 60 head 24 of the bit 22, will be efficiently re-

volved first in one direction and then in the other through the medium of the shaft 13 by the pinion 14, which pinion is revolved first in one direction by its frictional contact with the flange 9 of the wheel 8 and then in the opposite direction by its frictional engagement with the flange 10 of the wheel 8, but with a sufficient length of time between its differentiating movements occasioned by the flanges 9 and 10 due to the 70 substantially oppositely disposed spaces provided between the ends of one of the flanges and the ends of the other flange, this provision of the spaces between the flanges preventing the possibility of the flanges overlapping the operation of each other and eliminating the possibility of abnormal torque in the shaft 13 by the too sudden reversal of the direction of the pinion 14, and by the provision of the flexible connection 80 15, the operating end of the shaft 13 may be moved or swung in any lateral position and in any direction for grinding a plurality of valves and valve seats without having to move the engine or other object, and again, 90 by the provision of the telescopic connection within the hand-hold and between the outer end of the shaft 13 and the bit 22, the bit may be efficiently raised or lowered for effectively operating upon valves and valve 95 seats lying in different planes. Another advantage attained by this invention lies in the fact that the pinion 14 is frictionally driven which not only provides for the smooth rotation of the valve or valve seat 100 grinding tool but prevents any sudden jerks should the valve or valve seat grinding tool encounter obstructions such as chips, gaps and the like, and again, by forming one of the flanges substantially half way around 105 the circumference of the wheel 8 and the other flange substantially for one-third the distance around the remaining circumference of the wheel 8, the valve or valve seat grinding tool is given an efficient to and fro 110 movement and at the same time the valve or valve seat grinding tool will be advanced substantially one-sixth the distance of its rotary course, and provides for the more effectual and accurate grinding of the valve 115 and valve seats than can be attained by any of the devices now upon the market.

Having described my invention, what I claim as new and desire to secure by Letters Patent, is:—

In a valve grinding mechanism, a suspension frame having means at its upper end for attachment to a ceiling or other overhead support, a horizontal driving shaft journaled through said frame between its 125 upper and lower ends, a vertical driven shaft journaled through the lower end of the frame and extending downwardly for operating a valve tool, a beveled friction pinion secured on the upper end of the vertical 130

shaft within the frame, and a wheel secured on the horizontal shaft within the frame above said pinion, provided at opposite edges with outstanding arcuate flanges 5 having inner beveled friction surfaces to alternately engage opposite sides of said pinion, the spaces between the ends of said flanges being sufficient to permit the pinion to be disengaged from both flanges for an 10 interval, one flange being of an arcuate length of substantially one half of a circle,

and the other flange being of considerably less length whereby the flange of greater arcuate length rotates the vertical shaft farther in one direction than in the other. 15

In testimony whereof I have signed my name to this specification in the presence of two subscribing witnesses.

WILLOUGHBY S. SCOVILLE.
